UNITED STATES PATENT OFFICE.

EDWIN H. MARBLE, OF WORCESTER, MASSACHUSETTS, ASSIGNOR TO CURTIS & MARBLE MACHINE COMPANY, OF WORCESTER, MASSACHUSETTS, A CORPORATION OF MASSACHUSETTS.

CLOTH-SHEARING MECHANISM.

Application filed June 5, 1924. Serial No. 718,013.

To all whom it may concern:

Be it known that I, EDWIN H. MARBLE, a citizen of the United States, residing at Worcester, in the county of Worcester and 5 State of Massachusetts, have invented certain new and useful Improvements in Cloth-Shearing Mechanism, of which the following is a specification.

This invention relates to the novel construction of supporting rests for employment in cloth shearing machines, and the combination thereof with the shearing revolver and ledger-blade in machines of the class specified; the prime object being to 10 provide an efficient and desirable means adapted as set forth for the production of designs of a peculiar type, upon the surface of a sheared fabric.

Another object is to provide an assembled 20 revolvable rest, of interchangeable disk structure, the members of which can be readily re-assembled for forming a variety of patterns.

Another object is to provide an assembled 25 rest for the purpose specified, of interchangeable structure, including a system of separate plates and intervening spacing members arranged on a rotatable shaft and adapted for forming patterns composed of 30 series of dashes or broken lines, in various relations; or figures including such broken lines combined with continuous lines; change of figure being attained by re-assembling the disks or plates in their relative 35 order or positions.

A further object is to provide a cylindrical rest for the purpose specified comprising an assemblage of individually formed disks or plates interchangeably mounted and confined upon an axial shaft and externally presenting a system of segmental peripheral surfaces and intervening depressions, said disks or plates adapted for interchangeable re-assembling for varying the designs produced upon the sheared fabrics.

These objects I attain by a rest of the peculiar construction described, and its adaptation for use with the shearing cutters and operating means employed in a 50 cloth shearing machine, as more fully hereinafter set forth; the particular subject matter claimed being definitely specified.

In the drawings Fig. 1 is a sectional view

of such parts of a cloth shearing machine as will illustrate the nature of my invention.

Fig. 2 is a side view of my improved cloth supporting rest.

Figs. 3 and 4 represent forms of interchangeable disks or plates such as employed in the construction of the rest.

Fig. 5 is a cross-section of the rest at line X X, on Fig. 2;

Fig. 6 shows one of the inter-space members or washers.

Fig. 7 represents a modification wherein occasional individual annular disks formed with full circle peripheral edges are assembled in association with the series of peripherally segment-faced or recessed annular disks, in a rotatable cloth-shearing rest; and Fig. 8 is a side view of the full circle disk, equal to the diameter of the segment-faced disks employed.

Referring to the drawing, numeral 1 indicates the cutter-supporting frame of a cloth-shearing machine; 2 indicates the revolving cutter cylinder, commonly termed the revolver; 3 the ledger-blade or stationary knife; and 4 the means for adjusting the cutter frame up or down for regulating the cut in relation to the fabric to be sheared; all of which parts may be of well known construction and operated by mechanism of the usual character, and need not be herein more fully described.

Numeral 5 indicates my improved cloth supporting rest, which, in accordance with my invention, is composed of a series of comparatively thin annular disks or plates 6 about four inches, more or less, in diameter, and about one quarter inch, more or less, in thickness; said disks are assembled together with annular washers or spacing members 7, of less diameter, upon an axial shaft 8 whereon they are removably but rigidly secured or confined between nuts 9 screw threaded on the shaft, or by other efficient fastening means; a sufficient number of said disks and spacing members being assembled in series to fill the entire length required for the rest.

The edges of the disks 6 are shaped with protuberant segmental peripheral surfaces 10, alternating with recesses, or cut-away spaces 12, as best shown in Fig. 3 or Fig. 4. The relative dimensions and number of such

surfaces and recesses about the circumference of the disk may be varied in different instances. The central holes in the disks and intervening washers, are uniformly 5 made to concentrically fit the axial shaft 8, upon which said disks are interchangeably mounted and are arrangeable to afford some variety in the relative position of their assembled surfaces 10, in respect to the exterior of the rest. The intervening washers or spacing members 7 may be made of such thickness as in any instance required.

The shaft 8 is provided with journals 18, to be supported in bearings upon the shearing machine, and with a suitable pulley or gear 15 if it is desired to rotate the rest by power.

In some instances the disks 6 may be formed with different lengths of the segment surfaces 10, and assembled so as to produce irregular cut-out designs. Also, disks having segmental or incomplete peripheral lines may, in some instances, be associated with disks 6 having complete peripheral lines. The disks can be arranged and secured in fixed relation upon the axial shaft 8 more or less close together, or separated by washers 7 of greater or less thickness according to the design or pattern that it is desired to produce.

The working position of the rest in relation to the shearing revolver 2 and blade 3, is approximately as shown on Fig. 1; the cloth or fabric, indicated by dotted line 35 F, passing over the rest beneath the shearing cutters in the direction of the arrow. The rest 5 may be rotated by the friction and pull of the cloth thereon; or it can be rotated by power applied to the pulley or 40 wheel 15 on its shaft 8, and may when desired have a surface movement greater or less than the speed at which the cloth travels.

The nuts or fasteners 9 are made to hold the assemblage of plates entirely rigid upon the shaft 8 as a unitary structure, but said fasteners are conveniently releasable, and when one (or both) is released the series 45 of plates 6 and washers 7 can be readily disassembled and re-assembled in such order as may be desired for varying or changing the figure or pattern to be sheared upon the fabric. By this means a great variety of 50 patterns or figures, in the general style or character above mentioned, can be produced with a single rest, re-arranged as to its component parts, without requiring an entire new rest for every individual pattern.

Furthermore this invention renders it economically practical to produce a certain class 60 of patterns that have not heretofore been considered as available.

I claim—

1. A rotatable cloth-supporting rest comprising a series of separately formed interchangeable annular supporting plates, and intervening spacing washers, assembled and secured upon a central axial shaft, said series including plates having peripheral-edge faces of circumferentially alternated protuberant segmental-portions and recessed portions, as set forth.

2. A revolvable rest for the purpose specified, comprising a plurality of annular disks or plates and intervening smaller sized washers arranged and rigidly confined upon an axial shaft, the periphery of said plates having cloth-supporting faces and recessed portions alternately about their circumference.

3. A rest for cloth shearing machines, comprising an assemblage of separate annular plates and intervening spacing members, said plates having their peripheral edges variably provided with alternate segment surfaces and recessed spaces, an axis shaft upon which said plates are interchangeably supported, and means for rigidly securing the assembled parts together as a unitary cylindrical structure.

4. A revolvable rest including an interchangeable series of separately formed annular disk-like plates, a part of them having predetermined portions of the periphery reduced to form recesses in their circumference outline, an axial shaft upon which said plates are assembled, means for releasably confining said plates in position thereon, and means for rotation of said rest in coaction with the cutting revolver and ledger blade in a cloth shearing machine.

5. In a mechanism for shearing textile fabrics, a revolvable cloth-supporting rest composed of a series of narrow interchangeable annular members adjacently assembled and secured between removable nuts upon a central shaft, and peripherally presenting a system of segment surfaces and depressed spaces, said members adapted for varied relative arrangement in respect to each other, means for supporting said rest, and means for rotating the rest in conjunction with the shearing cutters and fabric feed, as set forth.

EDWIN H. MARBLE.
